FLUORESCENT LIGHTING FIXTURE

Edwin F. Guth, Florissant, Mo.

Application April 16, 1953, Serial No. 24,537

Term of patent 14 years

(Cl. D48—23)

To all whom it may concern:

Be it known that I, Edwin F. Guth, a citizen of the United States, residing in Florissant, county of St. Louis, State of Missouri, have invented a new, original, and ornamental Design for a Fluorescent Lighting Fixture, of which the following is a specification, reference being had to the accompanying drawing, forming a part hereof.

Fig. 1 is a bottom perspective view of a fluorescent lighting fixture, showing my new design, both sides of the device being identical; and

Fig. 2 is a fragmentary perspective view showing one corner of the device to a larger scale.

I claim:

The ornamental design for a fluorescent lighting fixture, substantially as shown and described.
